CLAIM

The ornamental design for a storage box, as shown and described.

DESCRIPTION

FIG. 1 is a perspective view of a storage box showing my new design.

FIG. 2 is a front view of a storage box.

FIG. 3 is a rear view of a storage box.

FIG. 4 is a left side view of a storage box.

FIG. 5 is a right side view of a storage box.

FIG. 6 is a top view of a storage box.

FIG. 7 is a bottom view of a storage box.

FIG. 8 is an exploded view of a storage box.

FIG. 9 is an enlarged view of a storage box taken from the circle part in FIG. 2.

FIG. 10 is an enlarged view of a storage box taken from the circle part in FIG. 4; and,

FIG. 11 is an enlarged view of a storage box taken from the circle part in FIG. 8.

The broken lines illustrate portions of the storage box and form no part of the claimed design; and the dash-dot lines illustrate the bounds of the enlarged view and form no part of the claimed design.
